UNITED STATES PATENT OFFICE.

HENRY S. SANDERSON, OF NEW YORK, N. Y., AND EDWARD B. SIMMONS, JERSEY CITY, NEW JERSEY.

PICTURE-EXHIBITOR.

SPECIFICATION forming part of Letters Patent No. 279,504, dated June 12, 1883.

Application filed February 13 1883. (No model.)

To all whom it may concern:

Be it known that we, HENRY S. SANDERSON, of the city, county, and State of New York, and EDWARD B. SIMMONS, of Jersey City, county of Hudson, and State of New Jersey, have invented certain new and useful Improvements in Picture-Exhibitors, of which the following is a specification, reference being had to the accompanying drawings, which to form a part of the same.

Our invention has relation to panoramic picture exhibitors for advertising; and its object is to provide a means for displaying a series of advertising in connection with a panoramic picture or a series of pictures; and the novelty consists in the construction of the same, as will be hereinafter more fully described, and particularly pointed out in the claims.

In the accompanying drawings similar letters of reference indicate like parts of the invention.

Figure 1 is a front elevation of our invention; Fig. 2, a rear view of the same. Fig. 3 is a longitudinal view in section, and Fig. 4 25 a transverse vertical section of the same.

A is the base and B the front, which may be of any suitable size, shape, and ornamentation.

C is the central opening in the front B, 30 through which the matter is exhibited.

D is the frame-work, in which is mounted the vertical main rollers E E, upon which the curtain G is mounted.

F F are two auxiliary rollers, which serve 35 to press the curtain against the opening C, so that its surface may be kept even and taut.

The rollers E E are provided at their lower ends with gears J J, which mesh in the pinions K K, having the crank-handles M M, by 40 which the main rollers and curtain are operated.

The top of the curtain is provided with a series of balls, a a, secured thereto on its upper edge at short intervals, and as the line of 45 the top of the curtain passes between the rails c c it is supported thereon by the balls a and

rides along horizontally on top of the rails, which prevent the curtain from sagging between the rollers.

O is a screw-rod, inserted in the bottom of 50 the main rollers E E, and is provided with a hand-adjusting wheel, P, by means of which the rollers may be raised or lowered vertically.

One end of the curtain being secured to one of the rollers E, the whole curtain is then 55 wound thereon, which may readily be done by removing it and placing in a frame in a horizontal position. The curtain is then passed between the rails c c, and the free end secured to the other roller, E, it of course having 60 been passed over the auxiliary rollers F F. It will thus be seen that the curtain can then be moved as desired by operating the crank-handles M M.

The surface of the curtain may be decorated 65 with any kind of attractive or interesting devices in addition to the advertisements desirable to display.

Having thus described our invention, what we claim as new and useful, and desire to secure 70 by Letters Patent of the United States, is—

1. A picture-exhibitor consisting of the frame D, having main rollers E E and auxiliary rollers F F, and curtain G, having balls a a on its upper edge, supported on the rails c c 75 and adapted to be moved horizontally on said rails, substantially as and for the purpose set forth.

2. The combination, with the main rollers E E, auxiliary rollers F F, and curtain G, having balls a a on its upper edge, supported on rails c c, of the screw-rods o o, and hand adjusting-wheels P P, as and for the purpose set forth.

In testimony whereof we affix our signatures in presence of two witnesses.

HENRY S. SANDERSON.
EDWARD B. SIMMONS.

Witnesses:

JOHN G. COOLY,
JOHN C. STANDER.
